UNITED STATES PATENT OFFICE

CHARLES C. SPREEN, OF DETROIT, MICHIGAN, ASSIGNOR TO KELVINATOR CORPORATION, OF DETROIT, MICHIGAN, A CORPORATION OF MICHIGAN

REFRIGERATING APPARATUS FOR BOTTLED GOODS

Application filed April 25, 1927. Serial No. 186,433.

This invention relates generally to mechanical refrigerating apparatus and especially relates to apparatus of the character indicated adapted for refrigerating packaged goods, bottles or the like.

A considerable trade in soft drinks and the like has been built up in conjunction with the soda fountain business, and many types of mechanically refrigerated structures for storing such packaged or bottled goods have been employed, some of which are a component part of the mechanically refrigerated ice cream cabinet, while others are separate structures which may be operated separately or may be operatively connected with the mechanical refrigerating apparatus associated with the ice cream cabinet. In all of such structures heretofore employed the cooling unit of the refrigerating apparatus was immersed in a bath of brine, water, or other fluid medium, which in turn contacted with the goods to be cooled or with the walls of the chamber in which they were stored.

The aforementioned structures are objectionable in that the rate of cooling of articles is very slow, which necessitates storing goods therein for a considerable period of time before the desired temperature is reached. This in turn necessitates storing a considerable quantity of goods in the cooling chamber at all times, thus requiring the employment of a large container which not only absorbs considerable heat from the surrounding atmosphere and is therefore uneconomical to operate, but is expensive to build and is too large to be conveniently disposed on or near the soda fountain of any busy establishment.

The object of my invention is to provide an automatically mechanically refrigerated device which permits of cooling articles placed therein at a very rapid rate.

Another object of my invention is to provide a cooling device which is inexpensive to construct, economical in operation, which is sufficiently light in weight and small and compact in structure to permit of placing it in very convenient and accessible places without interfering with the use of other equipment, and which lends itself to being designed so as to have a particularly attractive

and cleanly appearance when placed within the view of customers.

For a more detailed understanding of my invention reference may now be had to the accompanying drawing which illustrates one form which my invention may assume, and in which:

Fig. 1 is a vertical, longitudinal, cross-sectional view through a device embodying my invention showing the means for supporting the articles which are to be refrigerated.

Fig. 2 is a view in elevation of one end of the apparatus showing the hinged door for closing the entrance to the food storage compartment.

The structure illustrated comprises a cylindrical sleeve member 10 mounted upon suitable supporting legs 11 and provided at one end with a hinged door 12 and with a second hinged door 13 on the upper portion of the cylindrical surface adjacent the opposite end of the cylinder. Disposed within the cylinder 10 and spaced therefrom is a second cylinder 14, which is insulated from the cylinder 10 by means of a quantity of ground cork 15, or other suitable heat insulating material. The cylinder 14 is provided at one end with an opening 16, of relatively small diameter, which is in alignment with the hinged door of the cylinder 10. Disposed within the cylinder 14 is a tube or cylinder 17 having a relatively long straight portion 18 and a relatively shorter curved portion 19. The end of the straight portion 18 of cylinder 17 is welded or otherwise suitably united to the edges of the opening 16 in the cylinder 14, so as to form a gas tight union therewith. The curved end 19 of the tubular member 17 projects through an opening 20 in the side of the cylinder 14, and is welded or otherwise suitably secured to the edges of an opening 21 in the cylindrical surface of the cylinder 10, which opening is covered by means of the cover or door 13. The edges of the opening 20 in the cylinder 14 are welded or otherwise secured to the curved end 19 of the tubular member 17 so as to form a gas tight union therewith. Intermediate the ends of the cylinders 14 and 10, and in alignment with the tubular member 17, is disposed an annular

member 22, which serves as a passageway between the end of the tube 17 and the opening in the end of the container 10 which is closed by means of the door 12. The tubular member 17 is adapted to serve as a container and passageway for articles to be refrigerated, the drawing showing a plurality of bottles disclosed therein.

The end of the cylinder 10 opposite the door 12 is provided with an annular member 23 which serves to support an end member 24 within which is disposed an inlet port 25 and an outlet port 26, which communicate with the interior of the cylinder 14, and are provided with suitable connections 27 and 28, respectively, by means of which the evaporator is connected to a compressor-condenser unit (not shown) of a mechanical refrigerating apparatus. The inlet port 25 is provided with a float valve 29, of the type usually employed in refrigerating systems of the flooded type, which serves to regulate the flow of liquid refrigerant into the cylinder 14 and to maintain it therein at a substantially constant level. The end member 24 is welded or otherwise secured to the end of the cylinder 14 so as to form a gas tight union therewith. As illustrated, a body of refrigerant 30 is admitted through the inlet port 25 and comes into direct contact with the food storage tube 17, and as it evaporates it passes out of the evaporator in the form of gas through the outlet port 26. The doors 12 and 13 are each provided with springs 31, which serve to keep them normally in a closed position.

It will be apparent from the foregoing description that articles to be refrigerated are introduced into the apparatus by opening the door 12 and inserting them within the tube 17. The admission of each additional article to be refrigerated causes the articles previously introduced to be moved forwardly along the tube until they approach the door 13 which is opened manually and the desired article removed. By reason of the fact that the tube 17 is disposed in direct contact with the refrigerant 30, interiorly of the chamber in which the evaporation takes place, it will be apparent that they will be subjected to a very rapid cooling action and that it will be necessary for them to remain within the cooling device but a relatively short time in order to acquire the desired low temperature.

It will also be apparent that by reason of the compact structure employed, and the rapid rate of cooling to which the articles are subjected, as well as the relatively small number of articles contained within the chamber simultaneously, that the entire device may be of relatively small proportions and it may therefore be placed in many locations in which it is very accessible and in which it would be impossible to place the larger or old type cooling unit.

Although I have illustrated but one form

of my invention and have described in detail but a single application thereof, it will be apparent to those skilled in the art, that various modifications and changes may be made therein without departing from the spirit of my invention or from the scope of the appended claims.

What I claim is:

1. In a refrigerating apparatus, a container adapted to serve as an evaporator, a container adapted to surround said evaporator in spaced relation thereto, and a passageway through both of said containers, said passageway comprising a relatively long substantially straight portion and a relatively short curved portion, a door in the end of said outside container adjacent the end of said straight portion, and a door in the cylindrical surface of said outside container adjacent the opposite end thereof and adjacent the end of the curved portion of said passageway.

2. A refrigerating apparatus comprising a cylindrical casing member adapted to contain fluid refrigerant and provided with a door at one end thereof, a second door in the cylindrical surface of the casing in spaced relation to the opposite end thereof, and a cylindrical container for bottled goods disposed within the cylindrical casing member and surrounded by refrigerant fluid, the opposite ends of the container communicating with the aforesaid doors.

3. A refrigerating apparatus comprising a cylindrical casing, an elongated container having float controlled means associated therewith for maintaining a constant quantity of refrigerant liquid therein, and a curved container for bottled goods intersecting the cylindrical casing intermediate the opposite ends thereof.

4. A refrigerating apparatus comprising an outer casing, a curved container for bottled goods having an inlet portion in one wall of said outer casing and an outlet portion in a second wall of said outer casing, a container having a liquid refrigerant space and a refrigerant gas space, said container extending entirely around said curved container with a portion of said curved container being immersed in liquid refrigerant and a portion being exposed to said gas space, and float controlled means for maintaining a constant level of liquid refrigerant in the refrigerant container.

In testimony whereof I hereunto affix my signature.

CHARLES C. SPREEN.
